TETHERBALL

David Louis Senne, La Habra, Calif., assignor to W. J. Voit Rubber Corp., Los Angeles, Calif., a corporation of California

Application November 19, 1956, Serial No. 43,815

Term of patent 14 years

(Cl. D34—15)

Fig. 1 is a top plan view of a tetherball, showing my new design;

Fig. 2 is a side elevational view, the other sides having substantially the same appearance; and

Fig. 3 is a bottom plan view thereof.

I claim:

The ornamental design for a tetherball, as shown and described.
